UNITED STATES PATENT OFFICE.

MARSHALL C. LEFFERTS, OF NEW YORK, N. Y., ASSIGNOR TO THE ELECTRIC CUTLERY COMPANY, OF NEWARK, NEW JERSEY.

DESIGN FOR A RAZOR-HANDLE.

SPECIFICATION forming part of Design No. 21,013, dated August 25, 1891.

Application filed July 18, 1891. Serial No. 399,408. Term of patent 7 years.

To all whom it may concern:

Be it known that I, MARSHALL C. LEFFERTS, a citizen of the United States, residing in the city of New York, in the county and State of New York, have invented and produced a new and original Design for Handles of Razors, of which the following is a specification, reference being had to the accompanying drawings, forming a part thereof.

Figure 1 represents a face view of a razor-handle having my design applied thereto. Fig. 2 represents a back view of the same.

My design consists of the intaglio-rilievo ornamental figure *a* at the butt-end of the handle on the front face thereof, the line decoration *b*, resembling conventionalized flower and branch forms somewhat after the manner of Chinese decoration, near the middle of the front face of the handle, the intaglio-rilievo ornamental figure *c* at the butt-end of

the handle on the back face thereof, and the line decoration *d*, resembling conventionalized flower and branch forms somewhat after the manner of Chinese decoration, near the middle of the back face of the handle. 25

What I claim is—

1. The design for handles for razors, consisting of the figure *a* and line decoration *b*, substantially as shown.
2. The design for handles of razors consisting of the figure *c* and line decoration *d*, substantially as shown. 30
3. The design for handles of razors consisting of the figures *a* and *c* and the line decorations *b* and *d*, substantially as shown. 35
